UNITED STATES PATENT OFFICE

103,111

DESIGN FOR A LAVATORY UNIT

Walter W. Krolop, Bagley, Minn.

Application November 23, 1936, Serial No. 66,101

Term of patent 7 years

To all whom it may concern:

Be it known, that I, Walter W. Krolop, a citizen of the United States, residing at Bagley, county of Clearwater, State of Minnesota, have invented a new, original, and ornamental Design for a Lavatory Unit, of which the following is a specification, reference being had to the accompanying drawing, forming a part thereof, wherein

Fig. 1 is a front prospective view of a lavatory unit showing my new design, and

Fig. 2 is a top view of the same.

I claim:

The ornamental design for a lavatory unit, substantially as shown.

WALTER W. KROLOP.
